UNITED STATES PATENT OFFICE.

EDWARD COOPER POOLE, OF SOUTHAMPTON, ENGLAND.

REINFORCED BUILDING BLOCK OR SLAB.

No. 873,600. Specification of Letters Patent.

Patented Dec. 10, 1907.

Application filed January 19, 1906. Serial No. 296,842.

To all whom it may concern:

Be it known that I, EDWARD COOPER POOLE, civil engineer, a subject of the King of Great Britain, residing at 61 High street, 5 Southampton, in the county borough of Southampton, England, have invented certain new and useful Improvements in Reinforced Building Blocks or Slabs, of which the following is a specification.

10 My invention relates to armored or reinforced concrete construction, and comprises improvements in armored or reinforced concrete slabs, pieces, or blocks, and means for joining such slabs or blocks together to form 15 a monolithic whole, and in their combination to form permanent casings for concrete construction, or to enable concrete construction or work to be carried out or erected under conditions in which it would be difficult 20 or impracticable to execute such work, either as original, repair or supplementary work.

The main object of my invention is to provide reinforced or armored concrete slabs or pieces of various convenient portable sizes, 25 provision being made so that when the slabs or pieces are assembled, they may be joined together to form a monolithic whole, or to form a casing which when filled in with concrete, or concrete and metal in any form, 30 will become a monolithic whole in which the armor is so placed that an evenly distributed strain is provided for throughout the entire slab piece or structure.

According to and in carrying out my invention, I reinforce that is strengthen the concrete slabs or pieces by means of iron or steel bars of any approved section arranged to cross or recross the breadth, and also if desired, the length of each slab or piece in a 40 continuous diagonal alternating direction; the said bars where they are bent over at the edges of the slabs or pieces forming a series of loops or eyes which project somewhat beyond the edges of the slabs or pieces so that 45 when the slabs or pieces are brought together they may be connected by iron or steel rods.

In the accompanying drawings which form a part of this specification, I have shown my improved construction of reinforced concrete slab, piece or block, and have illustrated various ways of employing such slabs, pieces, or blocks assembled together, or of employing such slabs, pieces or blocks to 50 form casings for the construction, repair, or 55 strengthening of concrete or other work.

Description of the drawings.—Figures 1 and 2 show in plan the alternate lay of the iron or steel bars, and Fig. 3 is a plan of the block or slab broken away, showing the overlapping portions of the bar positioned at a point from the side edges of the block or slab.

In the drawings the same letters and figures are used to denote the same or corresponding parts throughout the various figures.

With reference to the drawings: *a* designates the iron or steel bar or bars which I employ, these may be of any approved section, and according to my invention are arranged to cross and recross the breadth, and if necessary or desired, the breadth and length of each block or slab in a continuous diagonal alternating direction without interrupting the continuity of the armor or reinforcing metal bar or rod, and so as to provide for an evenly distributed strain throughout the entire ferro concrete slab or piece.

The block or slab is formed of a body portion *c* of plastic material and has embedded therein a reinforcing member in the form of a bar *a*, the latter being bent to form a series of diagonally-extending portions of greater length than the width of the block, said diagonally-disposed portions overlapping each other and forming thereby eyes *b* projecting from the body portion *c* of the block. The parts of the diagonally-disposed portions which overlap are positioned within the block at a point removed from the side edges thereof.

d denotes a rod by which the adjacent slabs may be joined as hereinafter more fully described.

The concrete slabs or pieces *c* reinforced with the continuous bars *a* looped at *b*, are made in molds, the concrete being consolidated either by ramming in the usual way, or by pressure in hand or mechanical presses. The slabs or pieces *c* are then stacked to dry and mature; and when matured can be placed together so as to form the desired structure and immediately take the stress intended for them, thus allowing the work to proceed very rapidly, no waiting being necessary for the concrete in the structure to mature before loading it or plastering, or otherwise finishing it.

As previously stated, to join the slabs or pieces together, I employ iron or steel rods *d*

which I insert or place through the loops or eyes *b* of the reinforcing rods *a* on the meeting edges of the adjacent slabs *c*, thus joining piece to piece and the whole together; the joints or meeting edges of the slabs thus formed being then grouted together with cement mortar or other suitable material or substance.

What I claim as my invention, and desire to secure by Letters Patent is—

As a new article of manufacture, a building block comprising in its construction a reinforcing member and a body portion of plastic material within which said member is embedded, said member bent to form a series of diagonally-extending portions of greater length than the width of the block, said diag-

onally-disposed portions overlapping each other and forming thereby eyes projecting from the body portion of the block, the parts 20 of the diagonally-disposed portions which overlap positioned within the block at a point removed from the side edges thereof, said eyes disposed in a plane with respect to each other so as to register with each other 25 for freely receiving a bonding member.

In testimony whereof I have hereunto set my hand in presence of two subscribing witnesses.

EDWARD COOPER POOLE.
